United States Patent Office.

CHARLES H. LITHGOW, OF CHICAGO, ILLINOIS.

Letters Patent No. 103,210, dated May 17, 1870.

IMPROVED KNIFE-POLISHER.

The Schedule referred to in these Letters Patent and making part of the same.

I, CHARLES H. LITHGOW, of the city of Chicago, in the State of Illinois, have invented an Improved Apparatus for Polishing and Scouring Knives, of which the following is a specification.

My apparatus consists, essentially, of two disks, made to rotate in a fixed case or cylinder, through the periphery of which the knives are inserted, so that their blades are interposed between the faces of said disks, which are provided with brushes and ribs, with intervening channels, arranged as hereinafter described; and

My invention consists in the manner of constructing the disks to secure equal and elastic pressure of the rubbing-ribs upon the surfaces of the articles scoured, and in the device for insuring uniform pressure and action of the disks on opposite sides of the knives at the same time.

In the drawing—

Figure 1 is a central vertical section;

Figure 2, a transverse vertical section; and

Figure 3, a fragmentary view, showing a portion of one of the disks, and the construction of the ribs upon their faces.

The cylindrical case A A may be made of wood or metal, or its parts of both, and supported upon feet B B.

It has a central shaft, C, with journals passing through the sleeve-bearings in the sides of the case, as hereinafter described.

This shaft carries two disks, D D, of a size nearly filling the interior of the case, and which revolve with the shaft when it is rotated by the winch E.

The disks are provided, on their proximate faces, with brushes f f and rubbing-ribs g g, the space occupied by the latter being about three-fourths and the former one-fourth of the area of the disks.

The knives to be operated on are inserted radially through apertures h h on the rim of the case, so that their blades lie between the adjacent faces of the disks, and are subjected to abrasion by the brushes and ribs, which are supplied with emery, or other suitable abrasive material, in the following manner:

A small quantity of emery is placed within the case, which falls, by its weight, to the lowest point.

Small scoops or scrapers i i, formed of sheet metal, are attached to the outer side of each disk, at the periphery, which are connected each with a passage, j j, through the disks, opening into the space between them, at a point near the axis, and between the brushes. As the disks revolve these mouths scoop up a portion of the emery as they pass the bottom,

which passes through and is discharged between the brushes, and thence distributed through the intervening grooves between the ribs; and this operation being repeated at each revolution, a constant and equal supply is maintained.

The space containing the ribs g g is divided into triangular sections, the bases of which are radial from the axis of the disks.

The ribs are preferably made of leather, though felt or other fibrous substances will answer. They are glued or otherwise fastened to the faces of the disks, and are in part maintained in position by interposed wooden strips l l, of less projection, which are also glued or securely fastened to the disks; but between each of the ribs and strips is first placed a strip of India rubber, m, on the back side, relative to the direction of rotation of the rib. This has the effect to support, by its elasticity, the leather rib, and cause it to maintain its position under use, while it admits of its yielding to extreme pressure.

The knives are inserted in the manner shown by dotted lines in figs. 1 and 2, their edges facing the direction of rotation, and their handles supported partially by the guards n n.

In order to maintain an equal pressure of the disks toward each other, and against the knives which lie between their faces, each journal of the shaft is provided with a sleeve, o o, bearing at its inner end against a shoulder on the shaft, and its outer one against a rubber cushion, p, which yields as a spring, the amount of pressure being regulated by the screw-nuts r r.

The operation is rapid and effective, both to polish and scour knives and other edge-tools.

I claim as my invention—

1. The disks D D, provided with the brush and sectional-ribbed faces, as described, in combination with the closed case A, substantially as and for the purpose described.

2. Forming the ribs with flexible supporting-strips m m, interposed between the former and securing-strips l l.

3. In combination with the shaft C and disks D, the sleeve-bearings o o, cushions p p, and adjusting-nuts r r, as and for the purpose set forth.

In witness whereof I have hereunto set my name in the presence of two subscribing witnesses.

CHAS. H. LITHGOW.
